PIERRE LINDET, OF PARIS, FRANCE.

PRINTING TELEGRAPHY.

Application filed November 21, 1922. Serial No. 602,430.

To all whom it may concern:

Be it known that I, PIERRE LINDET, of 108 Boulevard Saint-Germain, Paris, France, engineer, have invented Printing Telegraphy, of which the following is a full, clear, and exact description.

This invention relates to an electrical transmitting and receiving apparatus particularly applicable to telegraphy through wires and wireless telegraphy and so combined as to require no permanent synchronism between the emitting station and the receiving station or stations.

In the known telegraphic apparatus utilizing the code with five moments (Baudot code), the distribution of the line currents, to the emitting station and to the receiving station, is ensured by the use of distributing brushes rotating in synchronism.

20 In other apparatus, this distribution is ensured, by the use of currents of opposed polarity; in this case the emitting apparatus is so arranged that it sends out, each time a key is acted upon, five currents successively

25 in the line whatever may be the key depressed. The combinations characterizing the various signals are differentiated from each other in this case by the sequence of apparition of the polarities; at the receiving station the five electro-magnets of the translating device are respectively energized

30 independently from each other by the five emissions of line current. These five electro-magnets are usually employed for directing, towards the electro-magnet controlling the striking of the transmitted letter, the local current through the medium of contacts connected in series by the armatures of these five electro-magnets.

40 The invention essentially consists in a distributing system no longer requiring any permanent synchronism between the emitting station and the receiving station and permitting the use of the Baudot code with

45 currents of single polarity, the combinations of currents, which characterize the letters or signs, being differentiated from each other by the moments of apparition of the currents which constitute them.

50 This distributing system determines, upon emission of a signal (letter or sign) the moments during each of which there should take place either a closure of current or an absence of current. This system is reversible so that, when the apparatus acts as a re-

ceiver, it collects the line currents at the moments corresponding to those when they have been sent out. The system is operated by a first current sent out through the line which simultaneously operates at the transmitting station and at the receiving station or stations a sensitive relay which causes the operation of distributing relays in a number equal to that of the moments, these relays being arranged in cascade, that is to say in such a manner that each relay is operated by the closure of the preceding relay.

The synchronous operation of the two groups of relays (emitting group and receiving group) is ensured owing to the identical construction of the two stations; the constant of time of operation of all the relays is ensured by the use of armatures having the same mass, same air-gap and identically wound, fed under equal tensions at the two stations.

It is moreover to be noted that, contrarily to devices with permanent synchronism, the errors are not added; since the emission of each letter transmitted and its reception are governed by a common origin.

The invention is moreover characterized by the combination of this distributing system with:

1st. A keyboard similar to that of a writing-machine or typewriter and in which the striking of each key has for its effect:

(a) to establish a combination of contacts interposed upon different shunts, and to thus establish a special combination of shunts for every letter, cipher or sign;

(b) to then produce the sending out of a line current, every one of the combinations representing the letters, ciphers or signs being thus characterized, as in the code with five moments or periods for example, by a certain number of closures of current and by the moments when these closures takes place.

2nd. A selecting-translating system comprising contact-making relays or contactors, branched upon distinct shunts corresponding to the receiving moments, and the closure or keeping in the open position of which controls the local circuit of the printing electro-magnets; the combinations of current closures, different for each letter, cipher or sign, operating the corresponding contact-making relay or relays, and the position of the latter closing the local circuit, by success-

105 110

sive selections, upon the electro-magnet printing the letter or sign corresponding to the key of the transmitting keyboard which has been struck or lowered.

5 In virtue of its special combination, the present system of apparatus operates without any synchronism being maintained between the transmitting station and the receiving station or stations, whence following 10 advantages:

1st. Suppression of the motors and regulators maintaining the synchronism.

15 2nd. Possibility of transmitting to one or several stations branched upon the line without that the latter be obliged to start their motor and to put themselves into synchronism, and without the necessity to resort to any preparatory operation.

20 3rd. Saving of current of motors and reduction of wear of mechanisms which come into action only during the time a letter or sign is struck.

25 4th. Greater safety of operation, every letter or sign having its own characteristic which is independent of the synchronism of the two stations.

30 5th. Suppression of the adjustment as required by the synchronous apparatus for correcting the displacements which occur when the signals appear and which are due to the self-induction and the capacity of the line, this advantage among others allowing transmitting without any previous adjustment at two stations situated the one 35 at a few meters from the sending out apparatus, and the other at several hundred kilometers from the latter.

40 6th. Possibility of checking at the transmitting station the message sent and to keep a copy of the text sent out.

7th. Possibility of transmitting without being bound to observe a certain rate.

45 A mode of execution of the present system of transmitting and receiving apparatus will be hereinafter described with reference to the accompanying drawings in which:

Figure 1 is a vertical section of the transmitting keyboard, made according to line A—A of Figure 3.

50 Fig. 2 is a plan view.

Fig. 3 is a horizontal section made according to line B—B of Fig. 1.

55 Fig. 4 is a diagrammatic view showing the whole of the distributing system at the transmitting station and at the receiving station.

Figs. 5 and 6 show two modified forms.

Fig. 7 is a diagrammatic view showing the whole of the selecting-translating system.

60 As shewn in these drawings, the present apparatus comprises a sending out or transmitting keyboard similar to that of a typewriter or writing-machine and comprising for instance 32 keys each corresponding to 65 a letter, cipher or sign. The lever 1 of each

key, movable about an axis 2, extends beyond this axis and carries at its end a combination of hollow and projecting parts 3, 4, 5, 6, 7; the several levers of the keyboard carry different combinations each corresponding with a letter or a sign; for instance there will be five elements for every combination, as in the case of the code with five moments.

Opposite these five, hollow or projecting, elements or parts of the combinations carried by each lever, are arranged five cross-bars 8, 9, 10, 11, 12, carried at each of their ends from double cranked arms 13, 14, 15, 16, 17, movable about the axis 2 of the key. 70 levers 1. The lower branches of these arms carry contact cross-bars 18, 19, 20, 21, 22 which, in the position of rest, bear upon fixed contact-pieces 23, 24, 25, 26, 27; the latter are constituted, for instance, by small metallic cylindrical bodies, slotted upon a part of their height, and into which the contact-bars can enter.

Opposite these five, hollow or projecting, elements or parts of the combinations carried by each lever, are arranged five cross-bars 8, 9, 10, 11, 12, carried at each of their ends from double cranked arms 13, 14, 15, 16, 17, movable about the axis 2 of the key. 75 levers 1. The lower branches of these arms carry contact cross-bars 18, 19, 20, 21, 22 which, in the position of rest, bear upon fixed contact-pieces 23, 24, 25, 26, 27; the latter are constituted, for instance, by small metallic cylindrical bodies, slotted upon a part of their height, and into which the contact-bars can enter.

80 The device comprises furthermore a cross-bar 28 supported as the preceding ones at both ends by two double-cranked arms 29 movable about the axis 2 and upon the lower branches of which is mounted a cross-bar 30 carrying a contact-piece 31 which bears, when this bar is lifted, against a fixed contact 32. Every lever 1 is terminated by a hollow part 33, so as to act upon the bar 28 and to thus cause the lifting of the bar 30 only when the key is fully lowered.

85 The movable contacts operated by the levers of the keyboard are, in normal time, constantly urged to bear against the fixed contact-pieces through the action of returning springs.

90 The five contacts, made by the five contact bars, 8 to 12, and the five fixed contact-pieces, 23 to 27, are respectively branched upon five distinct distributing shunts which will be hereinafter described; the contact-piece 31 and the fixed contact 32 are 95 branched upon the line circuit, as will hereinafter be described.

95 By means of this device, the striking of a key has for its effect first to prepare, by a combination of contacts, and finally to close, 100 by causing the contact 31 to bear upon the fixed contact-piece 32, the line-circuit; the current of the battery-line is thus closed at one or several of the five moments or periods determined by the combination of hollow 105 and projecting parts carried by the key. To every letter or sign corresponds a different combination of current sendings; the several combinations of hollow and projecting parts corresponding to 32 letters or signs 110 are established, for instance, according to the code indicated in the following table in which every one of the five moments of each combination is indicated by the sign + in case a current is sent out through the 115 120 125 130

line, and by the sign — in case there is no current on the line.

15	Letter blank + — — —				Cipher blank — — + —									

The sign marked "Letter blank" and the sign marked "Cipher blank" indicate that the type-carrying bar operated by 20 the currents corresponding to these two combinations does not strike any type, but produces the shifting of the carriage carrying the paper through the medium of the whole of the suitable apparatus, in order to present 25 the place at which the printing is to take place, under one or the other of the types carried by the type-bars.

The two distributing devices at the sending station and at the receiving station (Fig. 30 4) are both constituted by five relays 34 to 38, 34^a to 38^a, formed of armatures which are capable of being attracted by the corresponding electro-magnets 39 to 43 and 39^a to 43^a; these armatures are each provided 35 with two distinct contacts the purpose of which is to close two distinct circuits, the upper contacts of said armatures controlling the line current and the lower ones controlling the local currents.

40 The relays 34 to 38 of the sending station are set in operation by the action of a relay 44. This relay closes the circuit of the local battery 45 on the electro-magnet 39 causing the operation of the armature 34 which, 45 through its lower contact, shunts the local current unto the electro-magnet 40 which draws or attracts the armature 35; the latter, on its turn, creates a new shunt in the following electro-magnet and so on until the 50 five electro-magnets are engaged.

The setting in action of the relays 34^a to 38^a of the receiving station is effected in absolutely the same manner under the action of the relay 44.

55 The origin of the cascade release of the five relays 34 to 38 at the sending station is determined by the closing of the contact 31, 32 (Figs. 1 and 4) which closes the current of the battery 46 upon the electro-magnet 60 of the relay 44. At the receiving station, the origin or start of release of the five relays 34^a to 38^a is determined by the action upon the relay 44^a of the current sent through the line wire 47.

65 The two distributors (at the sending and

receiving stations) come therefore simultaneously into action and as their construction is identical for both of them, they synchronously perform the same operations.

At the sending station, the upper contacts of the relays are connected with the line through the medium of switches or interrupters constituted by the fixed contact-pieces 23 to 27 and the movable contact-pieces 18 to 22 operated by the operating 70 key-board, as above described and shewn in Figure 1.

The line current first passes through the armature at rest of the relay 34 (initial current which operates at the two stations the 80 relay 44 and the relay 44^a), then, through the armature of the relay 35 and the contacts 23, 18 which allow to send or not a moment current 1, then through the armature 36 and the contacts 24, 19 (moment current 2 85 or not) etc. . . . so that the line is passed through by from one to five currents sent out at moments which are determined with reference to the origin according to the key which has been strucken. 90

These currents are received at the receiving station in the electro-magnets 48 to 52 which are controlled by the operation of the armatures of the distributing relays 34^a to 38^a of this station; the latter operate in 95 synchronism with the distributing relays 34 to 38 of the sending station, as above specified, and the five electro-magnets 48 to 52 receive respectively the moment currents 1 to 5. 100

The distributor at the sending station reassumes the position of rest as soon as the finger of the operator leaves the key of the key-board, the armature of the relay 44 being returned by a spring; the distributor at 105 the receiving station is returned to the position of rest by the action of an electro-magnet 53 which is excited by a local current controlled by the striking of the letter.

It is to be observed that the displacements 110 due to the self-induction or to the capacity of the line have no influence upon the synchronism of the two stations, as the origin or start of the release, being the sending of a current similar to the working currents, 115 is submitted to the same displacements as the latter.

This distribution of the five moments during each of which a current is passing or not through the line, is effected in the above 120 described device by electric relays, but it could also be effected by mechanical relays, each of which comprises an armature which is kept cocked or armed by a lock or tumbler the electrical release of the first armature 125 relieving at the end of the stroke the lock of the second one, and so on.

Figure 5 shows, by way of example, an arrangement of this distributing device with 130 mechanical relays.

As shewn in this drawing, the armature of the relay 44, at the moment where the latter is excited, meets at the end of the stroke, an angle-iron 54 the opposite branch of which retains by means of this lock the first distributing relay 34; this part 54 then releases the latter which operates under the action of its pulling spring; at the end of the stroke, the armature of this relay meets the angle-iron 55 which retains the following relay 35 and releases it, and so on. These successive operations of the relays have for effect to send the current through the line in passing successively into the five switches or interrupters, as previously stated with reference to the distributor with electrical relays. The recocking of the five relays 34, 35 . . . is operated by a mechanical drive, for instance, a rod 57 provided with fingers 58 adapted to act upon the five relays, this rod being set in motion by an electro-magnet 59, excited by a local current controlled by the striking of the letter, for example.

The recocking of the five relays 34, 35 . . . could also be effected by five electro-magnets 60, 61 . . . acting respectively upon these five armatures against the action of the pulling spring as shewn in Figure 6.

The present system moreover comprises a selecting-translating device, the purpose of which is to control the printing of the letter or sign the current combinations of which has been received in the electro-magnets 48 to 52.

This selecting device, schematically represented by way of example in Figure 7, is essentially constituted as follows:

According as to whether the electro-magnet 48 (moment electro-magnet 1) of the distributor at the receiving station is excited or not its armature 62 sends the local current coming from the battery 45^a and brought through the wire 63 to the armature 64 or 65 of the double relay 49 (moment electro-magnet 2); each one of these armatures 64, 65 according as to whether it is attracted or not leads the current to one or to the other of the armatures 66, 67, on the one hand, and 68, 69, on the other hand; these armatures forming part of the quadruple relay 50 (moment electro-magnet 3).

The moment currents 4 and 5 act respectively upon the relays 51 and 52, the armature 70 of the relay 51 being connected with the other pole of the battery 45^a, through the wire 71; when all the distributing relays have been engaged, the relay 51, which comprises an armature 70, and the relay 52 which comprises two armatures 72, 73, select in each of the groups of four electro-magnets 74, the first, the second, third or fourth electro-magnet. In these conditions, these two relays 51, 52, operate, in the group of four electro-magnets selected by the three

first relays 48, 49 and 50, the selection of one single striking electro-magnet.

This control by the two ends of the electro-magnets 74 allows to reduce the number of armatures which would necessarily be much greater in case the selection would be made by successive divisions into two at one of the ends only of the striking electro-magnets; in fact, in this case, the number of armatures would be of one for the first relay; two, for the second one; four, for the third; eight, for the fourth; and sixteen, for the fifth.

It is to be observed that the five above described contact-making relays do not control the flow of current in the striking circuit, but serve only to prepare these circuits through which the current passes at the end of the operation of the distributing relays which make the combination, that is to say when the relay 38^a has closed the local circuit of the battery 45^a on the wire 71; it is therefore necessary that the armatures of the contact-making relays, after having been excited, keep their positions until the combination is ended.

This result can be obtained by means of the following device:

Each contact-making relay comprises two coils arranged the one above the other on a common core, a working coil 48 to 52 above described and a polarization coil 75 to 79 (Fig. 4). A very weak current passes through these five polarization coils; this current is supplied to these coils by a shunt from the battery 45^a; this battery supplies the five coils 75 to 79 with the necessary current, from the moment of the operation of the relay 44^a (initial current) till the end of the combination.

The attraction of these coils, insufficient to cause the release of the contact-maker or contactor, is sufficient to keep it engaged, when this contact-maker has worked under the action of the working coil, in virtue of the reduction of the air-gap due to the displacement of the armature.

This prior polarization of the core of the contact-making relays has further the advantage of allowing a quicker and safer operation under the action of the very short currents received by the working electro-magnets.

The transmitting and receiving system which has just been described can also be used in connection with wireless telegraphy.

The devices for carrying out the invention which have just been described are only given by way of example and can be modified; thus, for instance, the combinations of hollow and projecting parts, instead of being carried by the key-board levers, could be provided on the cross-bars 8 to 12, in such manner that the five bars will show opposite each lever the combination of hollow

and projecting parts characterizing the latter or sign which is to be transmitted by the lowering or striking down of this lever.

Claims:—

5. 1. A printing telegraphic apparatus, particularly adapted to be used with telegraphy through wires and wireless telegraphy, permitting to send, by means of an operating keyboard, and to receive different combinations of line current emissions corresponding to different letters and signs, each combination being formed by a determined number of line current emissions produced at predetermined moments as in the five moment Baudot code, the said apparatus being characterized by the combination of the following elements: at the sending station, a device distributing the line currents successively emitted comprising: distributing relays the number of which is equal to the total number of the moments of the code, arranged in steps and connected together so that the successive actuation of each of them is effected by the operation of the preceding one, a line relay set in action upon depression of each of the keys of the operating key-board and producing the release of the first distributing relay, shunts branched on the line and corresponding to the various distributing relays so that these shunts can be successively put into the line circuit at the time their respective distributing relays are set in action and that the current is cut off in a shunt as soon as the following one is put into the line circuit, interrupters interposed in these shunts, the said interrupters being actuated by the operating key-board and permitting to effect the combinations of the multiple moment code, and at the receiving station, a device distributing the line currents successively received, comprising: distributing relays, a line relay and shunts presenting the same arrangement as at the sending station, utilizing electro-magnets interposed in the shunts so that the successive actuation of the selecting relays of this receiving station causes the closing of the line successively in the shunts and determines the successive setting in action of the utilizing electro-magnets.
2. In a printing telegraphic apparatus as claimed in claim 1, an operating key-board comprising: levers each carrying a key and respectively corresponding to the letters and signs to be transmitted, interrupters respectively interposed in the circuits of the distributing relays, bars respectively carrying the movable contacts of these interrupters, the said bars being transversely arranged relatively to the levers of the key-board, combinations of projecting or hollow parts carried by each lever and different for each letter or sign, the said combinations carried by each lever coming opposite said bars so that each lever of the key-board, when it is lowered draws along one or more of the said bars according to the combination of projecting or hollow parts it carries and thus forms by the setting in action of one or more of the interrupters interposed in the circuits of the distributing relays of the sending station, a different combination of contacts for each letter or sign, a line interrupter interposed in the line circuit, a cross bar carrying the movable contact of the said interrupter and so arranged as to be actuated by the levers of the keyboard after the action of these levers on the bars carrying the movable contacts of the interrupters interposed in the circuits of the distributing relays, the whole being combined in such a manner that these bars actuated during the first part of the lowering of a lever of the keyboard, have for effect to prepare the combination of the shunts passing through the distributing relays which corresponds to the letter or sign of the lowered lever and that the above mentioned bar actuated during the last part of the lowering of the lever, has for effect to throw the line current, which latter is successively distributed in these various shunts under the action of the distributing relays.
3. In a transmitting and receiving apparatus as under claim 1, a translating-selecting apparatus of the successive current sendings received at the receiving station comprising:—contact-making relays mounted on the shunts controlled by the distributing relays of the receiving-station,—striking electro-magnets branched upon a local circuit,—and means for effecting, under the control of the contact-making relays, by successive selections, the closing of the local circuit on the electro-magnet for striking the letter or sign corresponding to the stricken key.
4. In a transmitting and receiving apparatus as under claim 1, a translating-selecting device adapted to allow successive sendings of currents for exciting the striking electro-magnet corresponding to the stricken key, this device including:—a local battery, a first contact-making relay with a single armature,—a connection between the latter and one of the poles of the local battery—two distinct shunts into one or the other of which the current supplied from the local battery is sent or not according as to whether the said armature is attracted or not,—a second contact-making relay with two armatures to which end the two preceding shunts,—two other shunts corresponding to each one of these armatures and to the one or the other of which the current is sent according as to whether these armatures are attracted or not,—a third contact-making relay with four armatures to which lead respectively the four shunts controlled by the two armatures of the preceding contact-making relay,—two shunts correspond-

ing to each one of these four armatures and to the one or the other of which the current is sent according as to whether these armatures are attracted or not,—and so on until 5 the final number of shunts obtained is equal to the number of striking electro-magnets,—connections for respectively connecting these shunts with one of the ends of the striking electro-magnets,—connections between the 10 other end of the latter and the other pole of the local battery.

5. In a transmitting and receiving apparatus as under claim 1, a translating-selecting apparatus so arranged as to allow 15 the use of the successive current sendings for exciting the striking electro-magnet corresponding to the striken or lowered key, this device comprising:—striking electro- 20 magnets—two controlling devices so adapted as to operate respectively at the two

ends of the coils of these electro-magnets, the one of these devices comprising selecting devices as under claim 5, connections for connecting respectively the shunts thus obtained with groups of striking electro-magnets, the other controlling device comprising also selecting devices as under claim 5,—connections to connect the shunts thus obtained with the striking electro-magnets of each group,—a local battery of connections to 30 connect the two poles of said battery respectively, with the two controlling devices.

The foregoing specification of my "electrical transmitting and receiving apparatus, particularly adapted to be used in connection with telegraphy through wires and wireless telegraphy," signed by me this 10th day of November, 1922.

PIERRE LINDET.
